UNITED STATES PATENT OFFICE.

ROBERT MCKAY AND FRANK R. WELTON, OF DETROIT, MICHIGAN,
ASSIGNORS TO THE MCKENNEY BUTTON FASTENING COMPANY,
OF SAME PLACE.

STAPLE-SETTING MACHINE.

SPECIFICATION forming part of Letters Patent No. 662,495, dated November 27, 1900.
Application filed December 18, 1899. serial No. 740,722. (No model.)

To all whom it may concern:

Be it known that we, ROBERT MCKAY and FRANK R. WELTON, citizens of the United States, residing at Detroit, county of Wayne, 5 State of Michigan, have invented a certain new and useful Improvement in Fastener-Setting or Stay Machines; and I declare the following to be a full, clear, and exact description of the invention, such as will enable others skilled in the art to which it appertains to make and use the same, reference being had to the accompanying drawings, which form a part of this specification.

Our present invention is designed to provide an improved staple or fastener setting machine, the same being more specifically adapted for a stay-machine employing a two-pronged fastening.

Our invention consists of the construction, combination, and arrangement of devices and appliances hereinafter specified and claimed, and illustrated in the accompanying drawings, in which—

Figure 1 is a view in side elevation. Fig. 2 is a vertical longitudinal section through the casing of the die-spindle. Fig. 3 is a front elevation of the plunger. Fig. 4 is a cross-section on the line 4 4, Fig. 3. Fig. 5 is a detail view of the lower extremity of the fastener-holding arm.

Certain features of the machine embodied in the drawings and specification submitted herewith are also embraced in a certain application for a button-setting machine, Serial No. 740,721, filed by us December 18, 1899, the button feeding and holding mechanism embodied in the accompanying application for a button-setting machine, together with other parts thereof, being in this instance omitted and certain additional features being incorporated herewith to adapt the machine more particularly for a stay-machine or a machine especially designed simply for setting the fastenings on different kinds of work, for staying seams on different kinds of work, and for analogous uses, such a machine being commonly termed a "stay-machine."

Accordingly in the drawings, *a* represents a suitable supporting-frame in which is jour-

naled a driving-shaft *b*, provided with a driving-wheel *c*, driven from any suitable source of power. Upon said shaft is a driving-cam *d*, preferably provided with a cam-groove *e*. A fastener-hopper is indicated at *f*, arranged to deliver fastenings to a fastener-runway *g*, 55 constructed with a customary channel or way 13, in which the fasteners pass to position to be engaged with the work. The fastener-hopper, it will be understood, may be provided with any desired feeding device to feed 60 the fasteners to the runway. The feeding device and runway forming no special subject-matter of the present invention need not be herewith particularly described.

A setting-die is indicated at *h* and the die-spindle at *i*, provided with a die *j*. Said spindle has a yielding movement in a plunger *k*, having a reciprocatory movement in a case *l*, which is a part of the frame *a*. In our present machine the fasteners are held adjacent 70 to the lower extremity of the die *j*, when the die descends the prongs projecting downward and the work being located upon the setting-die *h*, the prongs of the fastening being projected through the upper face of the work 75 against the setting-die therebeneath. To hold the fasteners, we employ a fastener-holding arm *m*, secured to a block *n*. This block is engaged in a dovetailed bearing or recess *p* in the plunger *k*, the case *l* being formed with 80 an opening at *r* to permit the engagement of the block with the plunger and to allow the plunger to have a limited movement in said case independent of the block. A spring *v* exerts its tension to raise the block until it 85 comes in contact with the case at the upper end of the orifice *r*, as at *q*, the upward movement of the block being limited thereby. The arm *m* is pivotally engaged with the block, as indicated at *s*, and is formed toward 90 its upper end with a beveled inner contact-face *t* to contact with a beveled portion of the case, (indicated at *u*), and whereby when the two beveled faces are in contact the arm will be thrown outward, as indicated in dotted lines, Fig. 2, so that its lower extremity will be out of the way of the further descent of the die. The spindle *i* has a limited move-

ment only in the plunger *k*, permitted by a spring *w* in the plunger, which may be given any suitable tension by means of a screw *x* in the top of the plunger. It will be understood that the die-spindle travels with the plunger. The block *n* is forced downward with the arm *m*, secured thereto by the contact of the die upon the head of a fastener located between the die and the lower extremity of said arm. A spring *o*, secured to the upper portion of the block *n*, bears at its lower extremity against the arm *m* to restore the arm to normal position. It will be perceived that on the upward movement of the spindle and plunger the spring *v*, secured to the plunger at one extremity and to the block at the other extremity, holds said block, with the arm *m*, up against the end of the die *j* until the upper end of the block strikes against the upper end of the slot *r*, as at *q*, whereby the upward movement of the block is stopped, so that when the plunger has reached its limit of upward movement an opening is formed between the die *j* and the adjacent end of the arm *m*. The lower extremity of said arm is preferably formed, as indicated in Fig. 5, with a fork *12*, onto which the fastener drops from the runway. The dropper is so timed that a fastener will drop at a time when the die-spindle is at its upward limit of movement and when the block carrying the holder-arm *m* is held down by contact with the upper portion *q* of the slot *r*, leaving an opening between the lower extremity of the holder-arm and the die for the fastener to drop into position on the holder-arm. It will be observed that the arm *m* will be carried downward with the block for a sufficient distance to engage the extremities of the prongs of the fastening in the work, after which the arm *m* will be moved out of the way as the fastening is further driven to clench the prongs in the work.

A fastener is indicated at *y*. A fastener dropper is indicated at *z*. To actuate the spindle and the fastener-dropper, we employ a lever *12*, fulcrumed intermediate its extremities, as indicated at 2, the inner end of said lever being provided with a cam-roll *3*, engaged in the cam-groove *e*, as in the accompanying application above referred to. Said lever *12* is constructed and arranged to actuate the die-spindle essentially in the manner described in said pending application, the forward end thereof being engaged with the spindle. The fastener-dropper *z* is made oscillatory, the same being pivotally engaged at its upper end, as at 4, upon the fastener-runway. The lower extremity of the dropper is recessed, as indicated at 5, forming two adjacent forks *6* and *7* on either side the channel or way 13 of the runway, the latter fork being longer than the former. These forks are constructed as indicated more definitely in Fig. 6, each being provided with a ledge or flange 8 at its lower extremity, the one to engage under the head of the lower fastener

in the runway and the other to engage under one of the prongs of the fastener next above. The lever *12* is formed with a finger 9 to engage the dropper *z* as the forward end of the lever rises to force the lower end of the dropper toward the die-spindle or into position to engage the prongs of a fastener. Upon the descent of the lever *12* the finger 9 is moved in position to permit a spring 10 to actuate the lower end of the dropper in the opposite direction to remove the flanges of the fork *6* from the prong of the fastener supported thereon and permitting the fastener to drop off its flange, the flange of the fork *7* engaging the head of the fastening so dropped. The opposite movement of the dropper engages the flange of the fork *6* underneath the prong of the next fastener in the runway. The fork *7* being moved away, the lower fastening is permitted to drop. The lower portion of the runway is so shaped as to bring the fastener into position in the arm *m*, with the prongs projecting downward. The arm *m* holds the head of the fastener against the die *j* until said arm is withdrawn and until the prongs of the fastener enter the goods. It will be apparent that when the plunger moves downward the fastener will be held rigidly between the die and the lower extremity of the arm *m*. The lever *12* may be engaged with the plunger *k* in any suitable manner—as, for example, the plunger may be formed with a recess 11, in which the lever may be engaged with said plunger.

In Figs. 2 and 6 is indicated in full lines the position of the fastener upon the prong *6* of the dropper, the position of the fastener relative to prong *7* being indicated in dotted lines. In Fig. 2 it will be evident that when a fastener is dropped into position shown in dotted lines the prong *7* will have been moved to the left to support the head of the fastener upon its flange.

What we claim as our invention is—

1. In a fastener-setting machine, the combination with a case, of a reciprocatory plunger, a vertically-reciprocatory die-spindle and its die, a rotatable shaft, means to actuate the die-spindle operated by said shaft, an oscillatory fastener-holding device carried downward by the descent of said plunger to hold the fastener under the die, and means to lift said holding device, said fastener-holding device being oscillatory at right angles to said shaft, said fastener-holding device and said case provided with adjacent beveled faces to force said device outward when said spindle descends, and means to retract said device to normal position.

2. In a fastener-setting machine, the combination with a case, of a reciprocatory plunger engaged in said case, a die-spindle and its die carried by said plunger, a fastener-holding device to support a fastener under the die, a vertically-reciprocatory block with which said holding device is pivotally engaged and arranged to be depressed by the

downward movement of the plunger, means to move the holding device out of normal position as the die-spindle descends, means to retract said device, and means to reverse the movement of said block when the spindle ascends, said block projecting through said case to carry the lower end of the fastener-holder device outside the case, said plunger having a free movement upward after the block has reached the limit of its upward movement.

3. In a fastener-setting machine, the combination with a reciprocating die-spindle and its die, of a plunger carrying said spindle, a case about said plunger provided with an elongated opening, a block engaged in said plunger and actuated by the descent of the plunger, an arm to support a fastener under the die connected with said block, means to swing the arm out of normal position, means to retract said arm when the plunger rises, said block projecting through said case to carry the lower end of the fastener-holder device outside the case, and means to lift said block to the upper limit of said opening, said plunger having a free movement upward after the block has reached the limit of its upward movement.

4. In a fastener-setting machine for setting a two-pronged fastening, the combination with a fastener-runway provided with a channel, of an oscillatory fastener-dropper fulcrumed at its upper end, said dropper arranged to oscillate laterally and being vertically immovable at one side of said channel and having its lower end adjacent to the channel of the runway and means to laterally oscillate said dropper, the lower end of said dropper provided with flanges on opposite sides of said channel the one above the other, the upper flange of said dropper constructed and arranged upon the movement of the dropper in one direction to engage between the lower fastener and the next fastener thereabove and separate said fasteners, the lower flange arranged to drop a single fastening at a time on the opposite movement of the dropper.

5. In a fastener-setting machine for setting a two-pronged fastening, the combination with a fastener-runway provided with a channel, of an oscillatory fastener-dropper fulcrumed at its upper end, said dropper arranged to oscillate laterally and being vertically immovable at one side of said channel and having its lower end adjacent to the channel of said runway, the lower end of said dropper provided with flanges on opposite sides of said channel the one above the other and means to laterally oscillate said dropper, the upper flange constructed and arranged on the movement of the dropper in one direction to separate a single fastening toward the base of the runway and drop it to the lower flange upon one movement of the dropper, and the lower flange arranged to give a further drop to said fastening upon the opposite movement of said dropper.

6. In a fastener-setting machine for setting

a two-pronged fastening, the combination with a fastener-runway provided with a channel, of a fastener-dropper fulcrumed at its upper end at one side of said channel and having its lower end adjacent to the channel of the runway, said dropper arranged to oscillate laterally and being vertically immovable, the lower end of said dropper provided with flanges on opposite sides of said channel the one above the other, means to swing said dropper in one direction whereby the upper flange will separate a single fastening at a time from the runway, and means to swing said dropper in the opposite direction to release a single fastening at a time from the lower flange.

7. In a fastener-setting machine, the combination of a fastener-runway provided with a channel, a die-spindle, means to actuate said spindle, a laterally-oscillatory fastener-dropper fulcrumed at its upper end at one side of said channel, and means to oscillate said dropper formed with two adjacent forks the one projecting below the other and located on opposite sides of said channel, and provided with an intervening recess, said forks provided at their lower ends with flanges projecting toward the runway.

8. In a fastener-setting machine, the combination with a fastener-runway, of a laterally-oscillatory fastener-dropper fulcrumed at its upper end at one side of said channel, the lower end of said dropper formed with two adjacent forks the one projecting below the other and located on opposite sides of said channel, and provided with an intervening recess, said forks provided at their lower ends with flanges projecting toward the runway, the upper flange upon the movement of the dropper in one direction arranged to engage between the lower fastening and the fastening next above, and the lower flange of the dropper arranged to engage the head of the lower fastener in the runway and hold it in position until the return movement of the dropper.

9. In a fastener-setting machine having a die-spindle and a fastener-runway provided with a channel, the combination of a lever to actuate the spindle, and a laterally-oscillatory fastener-dropper fulcrumed at its upper end at one side of said channel, the lower end of said dropper formed with two adjacent forks the one projecting below the other and located on opposite sides of said channel, and provided with an intervening recess, said forks provided at their lower ends with flanges projecting toward the runway, said dropper actuated in one direction by said lever, and means to retract said dropper.

10. In a fastener-setting machine, the combination with a support, provided with a case, of a recessed plunger reciprocating in said case, a die-spindle carried by the plunger, a block projecting through the case and engaged in the recess of the plunger and de-

pressed by the descent of the plunger, a fastener-holding arm pivotally engaged to said block, means to force said arm out of normal position, means to retract said block, and means to retract said arm, said plunger having a free movement upward after the block has reached the limit of its upward movement.

11. In a fastener-setting machine, the combination with a support, of a plunger, a die-spindle and its die carried by the plunger, a block depressed by the descent of the plunger, means to retract said block, an oscillatory fastener-holding arm pivotally engaged with said block, means to force the arm out of normal position as the spindle descends, and means to retract the arm, said arm forced downward by contact of said plunger with said block, and by further contact of the die-spindle with a fastener supported upon said arm, said plunger having a free movement upward after the block has reached the limit of its upward movement.

12. In a fastener-setting implement, the combination with a support provided with a slotted case, of a recessed plunger, a die-spindle carried by said plunger, a sliding block engaged in the recess of the plunger and projecting through the slotted case, an oscillatory arm engaged with said block, means to force the arm out of normal position upon the descent of the plunger, means to retract the arm, and means to raise the block to the upper limit of the slot in said case when the plunger rises.

13. In a fastener-setting machine, the combination with a support provided with a case, of a plunger reciprocating in said case, an

oscillatory lever to actuate the plunger, a die-spindle, a sliding block intermediate of the ends of the plunger actuated by the descent of the plunger, means to retract said block, an oscillatory fastener-holding arm pivotally engaged at its upper end with said block and actuated by the descent of the spindle, means to retract said arm, means to move the lower end of the arm out of normal position, and means to restore said arm to normal position.

14. In a fastener-setting machine, the combination with a support, of a reciprocatory die-spindle, a lever to actuate said spindle, a fastener-runway, a laterally-oscillatory fastener-dropper fulcrumed at its upper end at one side of said channel, the lower end of said dropper formed with two adjacent forks the one projecting below the other and located on opposite sides of said channel, and provided with an intervening recess, said forks provided at their lower ends with flanges projecting toward the runway, said dropper actuated by the lever in one direction, a spring to actuate said dropper in the opposite direction, the upper flange of said forks arranged to engage between the lower fastener and the fastener thereabove, the lower flange arranged to engage the lower fastener and to release the lower fastener on opposite movements of the dropper.

In testimony whereof we sign this specification in the presence of two witnesses.

ROBERT MCKAY.
FRANK R. WELTON.
